A. A. THOMAS

COMBINED RADIO AND PHONOGRAPH CABINET

Filed Feb. 5, 1924

INVENTOR

Adolph A. Thomas.

UNITED STATES PATENT OFFICE.

ADOLPH A. THOMAS, OF NEW YORK, N. Y.

COMBINED RADIO AND PHONOGRAPH CABINET.

Application filed February 5, 1924. Serial No. 690,697.

My invention is for a combined radio and phonograph cabinet constructed to constitute a single piece of household furniture containing complete radio-receiving apparatus and phonographic reproducing mechanism. The amplifying horn of the phonograph mechanism is also utilized for the loudspeaker of the radio set, and there is means for acoustically connecting either mechanism 5 with the horn by merely adjusting a finger piece conveniently located on the cabinet. This finger piece, which may be simply a knob on the phonograph motor board or the radio panel, controls an acoustic valve mechanism in the cabinet for readily connecting either the tone arm of the phonograph or the telephone receiver of the radio set with the amplifying horn. No removal of the phonograph sound box or any other parts is 10 necessary to use the phonograph horn as an amplifier for the radio set. In its preferred form, the acoustic valve mechanism of my invention also performs the function of controlling the volume of sound issuing out of 15 the horn either from the sound box or from the telephone receiver.

The foregoing and other objects and advantages of my invention will become apparent from a detailed description of the accompanying drawings, which illustrate a cabinet embodying the features of my invention. In 20 these drawings,

Fig. 1 shows in perspective a combined radio and phonograph cabinet equipped with 25 my invention;

Fig. 2 is a plan view, partly in section, of a portion of the cabinet, showing the acoustic connection between the radio telephone receiver and the amplifying horn;

Fig. 3 is a side view, partly in section, to 30 show the connections for operating the valve which controls the acoustic connections of the horn with the tone arm and the radio set; and

Fig. 4 is an enlarged fragmentary view 35 showing the controlling valve in various positions.

A cabinet K, of any approved construction and design, contains phonograph mechanism P and radio receiving mechanism R. It will 40 not be necessary to describe either of these mechanisms in detail, since they are well understood and are purchasable in the open market in various forms and styles. So it will be understood that P represents any

suitable phonograph mechanism installed in the cabinet, and R is any practical radio receiving set.

In the particular instance illustrated, the cabinet has a right compartment 1 and a left 60 compartment 2. Doors 1' and 2', respectively, may be provided for these compartments. The right compartment 1, which houses the phonograph mechanism, has a top panel 3, usually called the motorboard, from the fact 65 that it supports the phonograph motor. Compartment 1 also contains a sound-amplifying horn H of suitable construction and design, and acoustically connected with the tone arm in the usual way. The horn H, 70 as in all standard or accepted makes of phonographs, is rigidly built into the cabinet.

The left compartment 2 is for the radio mechanism. A top panel 4, preferably in 75 line with motorboard 3, may support the adjustable hand members of the tuning units contained in the radio set. Or, if the radio parts are mounted in a box with a vertical front panel, the entire outfit may be placed 80 as a unit in compartment 2, leaving the front panel of the box at the open front of the compartment for easy manipulation of the finger pieces projecting from the panel. It is immaterial how the radio set is mounted 85 in the cabinet.

The radio set in the cabinet includes a telephone receiver S of suitable construction. There are many kinds of such receivers on the market, and are well known to 90 radio enthusiasts, so I need not describe the detailed construction of receiver S, which represents more or less diagrammatically any practical form of radio telephone receiver. I will now describe how the receiver 95 S may be readily connected with horn H without removing or even disturbing the sound box of the phonograph mechanism.

In the neck 5 of horn H is provided an opening 6 over which is secured a plate 7, 100 as by screws 8, or otherwise. Plate 7 has a cylindrical flange or extension 9 adapted to receive the end 10 of a suitable sound tube A. Preferably the end 10 of the tube is enlarged, as shown in Fig. 4, so that flange 105 9 of plate 7 forms substantially a continuation of the inner wall of the tube. The other or smaller end of tube A is connected to a pipe 12 mounted in the partition 13, which separates compartments 1 and 2. 110

The pipe 12 may be slidably mounted in partition 13, so that tube A may be easily inserted and removed. To bring the tube in connecting position, the end 10 thereof is slipped over the flange 9 of fixed plate 7; then the tube is adjusted until the small end is in line with pipe 12, whereupon the pipe is pushed into engagement with the tube. This construction provides an exceedingly simple and yet firm mounting for the connecting tube A. The radio receiver S is adapted to be inserted into pipe 12 from the radio compartment 2, and may remain in that position, where it is easily accessible, as seen in Fig. 2.

A suitable valve controls the communication between tube A and horn H. In the broad aspect of my invention, this controlling valve may be mechanically embodied in various ways. For the sake of illustration, I have shown a valve 14 pivoted at 15 to plate 7 and so constructed as to close the opening 6 in the neck of the horn when the latter communicates with the tone arm. This closing or normal position of valve 14 is shown in full lines in Fig. 4. When the valve is swung over into the dotted-line position 14^a, the horn is closed against the tone arm and freely open to the sound tube A. The angular position 14^a of the valve is such that sound waves issuing out of tube A are deflected by the valve through the horn, which is thus in effect a continuation of tube A. This produces a gradually expanding and closed sound conduit of great length, from the telephone receiver S to the mouth of the horn, thereby effecting a powerful amplification of the vibrations of the diaphragm in the receiver. As seen from Fig. 2, this long sound conduit has no undue breaks or corners, thus reducing losses and distortion of tones.

The controlling valve 14 may be operated by any suitable connections. In the drawings, there is a rod 16 extending upwardly from the pivot of the vane. To the free end of rod 16 is fixed an arm 17 pivotally connected to one end of a link 18. The other end of link 18 is pivotally connected to the free end of an arm 19 fixed to and projecting laterally from a rod 20. The upper end of rod 20 is connected to a suitable finger piece, such as a rotary knob 21 mounted at a convenient point on the motor-board 3. If desired, a pointer 22 may be connected with the knob 21 to move therewith over a suitably marked plate or dial. When the knob is turned to the "Radio" position, as illustrated in Fig. 2, the valve 14 is in full open position, as indicated by the dotted lines 14^a. This means that the telephone receiver is in full communication with horn H. To connect the tone arm with the horn, it is only necessary to turn the knob 21 into the position marked "Phone"

in Fig. 2, whereby the connections previously described move the valve 14 to clear the neck of the horn and close the opening 6.

It has been demonstrated that in amplifying horns it is necessary for the proper practical operation of the horn, especially on low frequencies, to avoid sharp right-angled bends, since these tend to throw the sound back. In the curved sound conduit A—H there is no right-angled bend, for the valve 14, when in position 14^a, acts like a gradually curved connection between tube A and horn H. In the absence of valve 14, the sound issuing out of tube A would strike the opposing wall 5 of the horn, and since that wall is practically at right angles to the direction of movement of the sound waves, the wall would tend to repel such waves into the tube. Furthermore, without a controlling valve at the junction of tube A with horn H, it is evident that sound waves entering the horn would be divided into two paths—some issuing through the mouth of the horn and others going through the neck of the horn into the tone arm, where they would be lost as in a cul-de-sac. The result would necessarily be a weak muffled reproduction with unnatural tone qualities. These objections are entirely overcome by the valve 14.

The valve 14 also performs the additional function of controlling the volume of sound issuing out of the horn either from the telephone receiver or the phonograph sound box. Referring to Fig. 4, it will be seen that, if the valve 14 is moved to an intermediate position, as indicated by the dotted lines 14^b, the passage between tube A and horn H and also the passage between the tone arm and the horn will be restricted. The result is a reduction in the volume of sound issuing out of the horn. The volume is regulated in accordance with the position of the valve, which may be visually indicated to the operator on a scale associated with pointer 22. It will be understood that valve 14 is so mounted and constructed that it remains firmly in any adjusted position, as by friction or otherwise.

My invention is readily installed in phonograph cabinets of standard or previous designs. The tube A is easily connected to the phonograph horn, and the controlling valve 14 with its operative connections can be put in place without difficulty and without mutilation of the cabinet. It goes without saying that when I speak of a radio-phonograph cabinet I do not necessarily mean a cabinet which is fully equipped with radio-receiving apparatus, for such apparatus forms no part of my invention. It is immaterial whether the telephone receiver to be amplified through the valve-controlled sound passage is connected with a radio set within the cabinet or out-

side the cabinet. It is obvious that the practical advantages of my invention are fully realized in a phonograph cabinet equipped with my novel means for acoustically connecting a telephone receiver with a phonograph horn, irrespective of where the radio set is situated.

It will be seen from the foregoing that I have provided a simple and convenient means for utilizing the horn of a phonograph cabinet as a loudspeaker for a radio set without the trouble of having to remove the sound box. A little twist of knob 21, or whatever kind of finger-piece may be used, is all that is necessary to connect either the tone arm or the radio telephone receiver with the amplifying horn. By bringing the small end of tube A out near the front of radio compartment 2, the receiver S is in a handy position for removal and replacement.

If desired, the cabinet may be made entirely self-contained as a radio cabinet by providing it with a receiving loop.

Although I have herein shown and described a specific construction, I want it understood that I have done so merely to explain my invention by means of an illustrative embodiment, and not by way of restriction or limitation. Changes and modifications will doubtless occur to those skilled in the art, without departing from the scope of the invention as defined in the appended claims.

I claim as my invention:

1. In a radio-phonograph cabinet, the combination of a phonograph horn communicating with a tone arm, a sound tube acoustically connected with said horn, a telephone receiver adapted to be connected with said tube, a rotary valve for acoustically connecting said horn either with said tone arm or with said tube as a common sound amplifier for both, a vertically mounted rod for operating said valve, and a finger piece at the top of said cabinet for actuating said rod.

2. In a radio-phonograph cabinet, the combination of a phonograph horn connected with a tone arm, a sound tube acoustically connected with said horn independently of the tone arm, means for supporting said horn independently of said sound tube, a rotary valve for controlling the acoustic connections of the tone arm and the sound tube with said horn, means for so mounting said valve that it remains in any adjusted position to control the volume of sound issuing out of said horn from either the tone arm or the sound tube, and means for manually controlling the position of said valve.

3. In a radio-phonograph cabinet, the combination of a phonograph horn connected with a tone arm, a telephone receiver acoustically connected with said horn independent-

ly of the tone arm, a horizontally movable vane for controlling the acoustic connections of the tone arm and the telephone receiver with said horn, means for so mounting said vane that it remains in any adjusted position to control the volume of sound issuing out of said horn from either the tone arm or the telephone receiver, and a rotary finger piece projecting from the cabinet for manually controlling the position of said vane.

4. In a radio-phonograph cabinet, the combination of a phonograph horn communicating with a tone arm, a sound tube acoustically connected with said horn, a swinging vane for acoustically connecting said horn either with said tone arm or with said tube, whereby said horn acts as a common sound amplifier for said tone arm and said tube, a vertically mounted rod connected with said vane, and a rotary finger piece at the top of said cabinet for turning said rod to swing said vane into the desired position.

5. In sound-reproducing apparatus, a cabinet having a sound-amplifying horn provided with an opening intermediate the neck and mouth of the horn, a plate secured over said opening, a tubular flange on said plate in line with said opening, a support in said cabinet, a pipe slidably mounted on said support, a sound tube supported at one end on the flange of said plate and at the other end on the projecting end of said pipe, said pipe being adapted to be connected with a source of sound to be amplified through said tube and said horn, and a manually adjustable member for controlling the sound opening at the junction of said tube and said horn.

6. In sound-reproducing apparatus, a cabinet having a sound-amplifying horn provided with an opening intermediate the neck and mouth of the horn, a plate secured over said opening, a tubular flange on said plate in line with said opening, a support in said cabinet, a pipe slidably mounted on said support, a sound tube supported at one end on the flange of said plate and at the other end on the projecting end of said pipe, said pipe being adapted to be connected with a source of sound to be amplified through said tube and said horn, a vane pivoted on said plate and arranged to open and close said opening in the horn, and means for controlling said vane.

7. In a radio-phonograph cabinet, the combination of a phonograph horn connected with a tone arm, a sound tube of substantial length connected to said horn intermediate the neck and mouth of the horn, means for supporting said horn independently of said sound tube, a telephone receiver connected to the free end of said tube, a movable vane mounted at the junction of said tube and said horn, means whereby said vane closes said horn against the tone arm and acts as

- a deflector of sound waves from said tube through said horn, said vane being also constructed to close said tube and open communication between the tone arm and the 5 horn, whereby said vane not only controls the acoustic connections of said tube and said tone arm with said horn but also acts in intermediate positions to control the volume of sound issuing out of said horn, means 10 for so mounting said vane that it remains not only in either of its final positions but also in any of its intermediate positions, and means for manually controlling the position of said vane.
- 15 8. In a radio-phonograph cabinet, the combination of a phonograph horn communicating with a tone arm, a telephone receiver, a sound conduit between said receiver and said horn independent of the tone arm, 20 a movable finger piece on the top board of said cabinet, and a single valve member operated by said finger piece for connecting either the tone arm or the telephone receiver with said horn.
- 25 9. In a radio-phonograph cabinet, the combination of a phonograph horn communicating with a tone arm, a telephone receiver, a sound conduit between said receiver and said horn independent of the tone 30 arm, a pivoted finger piece on the top board of said cabinet, and a pivoted valve operated by said finger piece for connecting either the tone arm or the telephone receiver with said horn.
- 35 10. In a device of the character stated, a horizontally disposed amplifier, inlets leading to the rear thereof from a plurality of sound reproducing devices, and a vertically disposed tone modulator pivoted at the rear 40 of said amplifier capable of lateral movement and extending towards the exit portion thereof and controlling the exit of sound waves from either of said inlets.
- 45 11. In a radio-phonograph cabinet, the combination of a phonograph horn communicating with a tone arm, a sound tube mounted in fixed position within the cabinet and leading into said horn, a telephone receiver connected to the free end of said tube, 50 a movable finger piece arranged over the top board of said cabinet, a single valve member separate from said finger piece and mounted independently thereof, and a connection between said finger piece and said 55 valve for operating the latter to connect either the tone arm or the telephone receiver with said horn.
- 60 12. In a radio-phonograph cabinet, the combination of a phonograph horn communicating with a tone arm, a telephone receiver, a sound passage between said receiver and said horn independent of the tone arm, a turnable valve for connecting either 65 the tone arm or the telephone receiver with said horn, a finger piece projecting above the topboard of said cabinet and so mounted as to be turnable horizontally about a vertical axis, and an operative connection between said finger piece and said valve.
13. In a radio-phonograph cabinet, the 70 combination of a phonograph horn communicating with a tone arm, a telephone receiver, a sound passage between said receiver and said horn independent of the tone arm, a turnable valve for connecting either 75 the tone arm or the telephone receiver with said horn, a rotary member vertically mounted within the cabinet, a knob arranged on the topboard of the cabinet and fixed to the upper end of said member, said knob being horizontally turnable in opposite directions to rotate said vertical member, and means for operatively connecting said member with said valve.
14. In a radio-phonograph cabinet, the 80 combination of a phonograph horn communicating with a tone arm, a sound tube mounted within said cabinet below the topboard thereof and communicating at one end with the neck of said horn, a telephone receiver connected to the other end of said tube, a single valve member mounted at the junction of said tube and horn for interchangeably connecting either the receiver or the tone arm with said horn, a pivoted finger 85 piece projecting above the topboard and mounted independently of said valve, and a movable connection between said finger piece and said valve.
15. In a radio-phonograph cabinet, the 90 combination of a horn mounted in the cabinet below the topboard thereof and communicating with a tone arm, a telephone receiver within the cabinet below said topboard, a sound tube connecting said receiver 95 with the neck of said horn, a valve for interchangeably cutting off communication of said tone arm and said tube with the phonograph horn, a pivoted handle mounted on the topboard independently of said valve, 100 and a system of levers connecting said handle with said valve for actuating the latter.
16. In a radio-phonograph cabinet, the combination of a phonograph horn communicating with a tone arm, a sound tube fixed 105 within said cabinet below the topboard thereof and connected at one end to said horn, a telephone receiver at the other end of said tube, a single valve member mounted at the junction of said tube and said horn 110 for connecting either said tube or said tone arm with the horn, a movable finger piece projecting through an opening in the topboard of the cabinet, said finger piece being mounted independently of said valve, and a movable connection below said topboard 115 between said finger piece and said valve.
17. In a radio-phonograph cabinet, the combination of a phonograph horn communicating with a tone arm, a sound tube 120

- acoustically connected with said horn, a telephone receiver adapted to be connected with said tube, a single valve member for acoustically connecting said horn either with said 5 tone arm or with said tube as a common sound amplifier for both, a vertically mounted rod for operating said valve, and a finger piece at the top of said cabinet for actuating said rod.
- 10 18. In a radio-phonograph cabinet, the combination of a phonograph horn communicating with a tone arm, a sound tube acoustically connected with said horn, a valve for acoustically connecting said horn either with said tone arm or with said tube, whereby said horn acts as a common sound amplifier for said tone arm and said tube, a vertically mounted rotatable rod connected with said valve, and a turnable finger piece 15 at the top of said cabinet for turning said rod to actuate said valve into the desired position.
19. In a radio-phonograph cabinet, the combination of a phonograph horn communicating at its inner end with a tone arm, a tube mounted in fixed position below the motorboard of the cabinet and connected at its inner end with said horn, a telephone receiver connected with the other end of said 25 tube, a horizontally swinging valve plate pivoted on a vertical rod at the junction of said tube with said horn, and a rotatable finger piece on the motorboard connected to said rod for actuating said valve plate.
20. In a radio-phonograph cabinet, the combination of a phonograph horn, a tone arm mounted on the rear portion of the motorboard of said cabinet and communicating with said horn, a branch tube acoustically 30 connected at its inner end with said horn below the motorboard, a telephone receiver connected with the other end of said tube, a horizontally swinging valve plate pivoted at one end on a vertical rod at the junction of said tube with said horn, a rotatable finger piece mounted on the motorboard back of the turntable and connected to said rod for actuating said valve plate, and a pointer movable with said finger piece over the motorboard to indicate the position of said valve plate.
21. In a radio-phonograph cabinet, the combination of a phonograph horn communicating at its inner end with a tone arm, the neck of said horn having an opening in one of its vertical walls, a tapering radio reproducer arm arranged horizontally in said cabinet below the motorboard thereof, means for connecting the larger or base end of said reproducer arm to said vertical wall of the horn to cover said opening, a radio telephone receiver connected to the small or free end of said reproducer arm, a valve plate pivoted at one end in the neck of said horn for connecting either the telephone re- 35 ceiver or the tone arm with said horn, a rod extending from said valve plate substantially in line with its pivotal mounting, and a finger piece outside the cabinet for turning said rod one way or the other to swing the 40 pivoted valve plate into the desired position.
22. In a radio-phonograph cabinet, the combination of a phonograph horn communicating with a tone arm, a sound tube acoustically connected with said horn below 45 the topboard of the cabinet and adapted to receive a telephone receiver at its free end, a turnable valve at the junction of said horn and tube for interchangeably connecting either the receiver or the tone arm with 50 said horn, said valve being provided with an axial extension, actuating means on said extension, a turnable finger piece mounted independently of said valve, a member connected to said finger piece and turnable therewith, said member extending below the topboard, and actuating means carried by 55 said member and operatively connected with the actuating means on said extension.
23. In a radio-phonograph cabinet, the combination of a phonograph horn communicating with a tone arm, a sound tube acoustically connected with said horn below 60 the topboard of the cabinet and adapted to receive a telephone receiver at its free end, a turnable valve at the junction of said horn and tube for interchangeably connecting either the receiver or the tone arm with said 65 horn, said valve being provided with an axial extension, actuating means on said extension, a turnable finger piece mounted on the topboard of the cabinet independently of said valve, a vertical member connected with said finger piece and turnable therewith, said member extending below the topboard, and actuating means at the lower end of said 70 member, said last-named actuating means being operatively connected with the actuating 75 means on said extension.
24. A combined radio-phonograph cabinet comprising a horn-shaped sound-amplifying chamber, a tone arm carrying a phonograph reproducer and communicating with said chamber, a sound tube mounted in fixed position within said cabinet and leading into 80 said chamber, a telephone receiver connected to the free end of said tube, a valve plate pivoted at the junction of said tube and said chamber, said valve plate in one position forming a continuation of said tube to connect the same with said chamber to the exclusion of said tone arm, said valve plate in another position closing off the sound tube and connecting the tone arm with said chamber, a rod rotatably mounted in said cabinet, 85 said valve being pivoted independently of said rod, means for connecting said rod at its inner end with the pivot axis of said valve, and a rotary finger piece at the outer end of said rod for turning the same in 90 95 100 105 110 115 120 125 130

either direction to operate said valve plate.

25. A combined radio-phonograph cabinet comprising a horn-shaped sound-amplifying chamber, a tone arm carrying a phonograph 5 reproducer and communicating with said chamber, a sound tube mounted in fixed position within said cabinet and leading into said chamber, a telephone receiver connected to the free end of said tube, a valve plate 10 pivoted at the junction of said tube and said chamber, said valve plate in one position forming a continuation of said tube to connect the same with said chamber to the exclusion of said tone arm, said valve plate 15 in another position closing off the sound tube and connecting the tone arm with said
- chamber, the pivot axis of said valve plate extending outside of said junction, an actuating member fixed on the outer extension of said pivot axis, a rod mounted in 20 said cabinet independently of said pivot axis and substantially parallel therewith, a second actuating member mounted on said rod at its inner end and operatively connected to said first-named actuating member, whereby rotation of said rod in either direction actuates said valve plate for connecting either said tone arm or said sound tube with the common amplifying chamber; and a rotary finger piece connected to the 25 outer end of said rod for actuating the same.

ADOLPH A. THOMAS.
